MOUNTING STRUCTURE FOR HORIZONTALLY PIVOTED WINDOWS

Werner M. Leeser, Cincinnati, Ohio, assignor to The Steelcraft Manufacturing Company, Rossmoyne, Ohio, a corporation of Ohio

Application February 18, 1953, Serial No. 337,488

3 Claims. (Cl. 189—69)

This invention relates generally to industrial windows and is directed in particular to an improved structure for pivotally mounting a ventilator sash, adapting the sash to be tilted selectively to open or closed positions for ventilation or weather protection.

Window units of this type are known in the building industry as horizontally pivoted windows since they consist in general of a window frame fixed permanently in a window opening, with the ventilator sash pivoted upon a horizontal axis near its center, such that the plane of the sash in tilted position intersects the plane of the frame. Both the window frame and sash are usually fabricated from metal framing members, in most instances steel rails, which are fitted and joined together by welding or riveting.

Horizontally pivoted windows are used extensively in commercial buildings, such as schools, offices, and factories, and are particularly suited for such utility since they are simple and rugged in construction and can be adjusted conveniently to open or closed positions. It will be recognized that a weather seal must be provided around the perimeter of the ventilating sash for cold weather protection and that weather sealing means must be provided in conjunction with the hinge or pivot connections to prevent leakage, since the pivot connections interrupt the continuity of the weather seal.

The hinge or pivot mountings utilized in the past have been unsatisfactory for several reasons. In one widely used form for example, the pivotal connections are attached to the frame and sash as separate elements, thus requiring a welding or riveting operation in assembling the window unit. Another disadvantage, which is common to the known pivot structures, arises from the fact that the parts project outwardly beyond the plane of the window unit; hence the parts are subject to impacts during handling and use, causing bending of the parts which leads to looseness or binding of the sash.

It has been a primary object of the present invention to provide a simplified sash mounting and weather sealing structure in which the pivot mounting occupies a concealed and protected position within the plane of the sash and window frame, and in which the pivot mounting constitutes an integral part of the window unit without requiring the use of separate hinge members and the attendant attachment of such parts by welding, riveting or the like.

A further object has been to provide a simplified mounting structure formed of sheet metal which is configurated to provide integral cooperating hinge members which are U-shaped in cross section to provide a plurality of metal sections in radial load bearing contact with a pivot pin, with the metal U-shaped sections in lateral bearing contact with one another to maintain the sash in accurate registry with the frame opening.

A further object has been to incorporate in the mounting structure a weather seal extending about the perimeter of the ventilator sash in cooperation with pivot seals which establish a wedging engagement, so as to com-

2

pletely weather seal the sash when it is shifted to closed position.

In its simplest aspect, the invention resides in the use of sheet metal weathering or mounting strips pivotally connected together intermediate their length and co-extensively attached respectively to the window frame and to the ventilator sash to pivotally support the sash relative to the frame and to provide a weather seal extending around the entire perimeter of the ventilator sash. One set of weathering strips extends upwardly from the pivotal axis and is secured along the vertical sides and top of the sash to provide the seal above the pivotal axis while the other set extends downwardly from the axis and is secured along the sides and bottom of the window frame to provide a seal below the pivotal axis.

The two sets of weathering strips are identical but since the upper and lower portions of the sash project from opposite sides of the frame when open, the strips of the respective sets are oppositely related to one another to provide abutments facing in opposite directions. In the present disclosure, the upper portion of the sash projects inwardly when opened and the lower portion projects outwardly; accordingly, the weathering strips for the upper portion are attached to the sash while those for the lower portion are attached to the window frame and support the weight load of the sash.

As noted above, an important aspect of the invention resides in the use of sheet metal weathering strips of U-shaped cross section, to function both as a seal and to provide a strong wear resistant pivotal connection within the plane of the weathering strip for protection and concealment. For this purpose the adjoining ends of the upper and lower weathering sets of strips are partially severed and doubled over to form corresponding tenons or hinge sections integral with the strips, each being U-shaped in cross section and being slightly less than half the thickness of the U-shaped weathering strip proper. The two tenons nest with one another in inter-fitted relationship and the pivot pin joins them together; thus the U-shaped configuration provides the multiple spaced bearings and the lateral or axial bearing surfaces without the addition of any parts except the pivot pin.

In order to provide the seal at the pivotal connection between the two sets of weathering strips, the ends of one set of strips, at the joint, are provided with sealing sectors as an integral part of the strips. The sectors establish seals with the ends of the adjoining set of strips when the sash is closed. The sheet metal construction of the tenons and sealing sectors is such that the parts are capable of being formed cheaply and accurately by punch and die operations. The structure forms a simple hinge or pivot connection having maximum strength and rigidity and presents a neat and trim appearance since there are no parts protruding from the surface of the sash or window frame.

Commercial steel pivoted windows are furnished in several different sizes and styles, all including a fixed window frame and a pivotally mounted ventilator sash. The larger sizes may be provided with additional panes in the fixed frame, partially or completely surrounding the ventilator sash and providing additional window area. It will be understood that it is intended to incorporate the present improvements in such larger frames without any change in structure. It will also be understood that the present ventilator sash can be installed in multiples, for example, individual units joined together by mullion strips.

Further advantages and features of the invention will be apparent from the following detailed description taken in conjunction with the drawings.

In the drawings:

Figure 1 is a perspective view of a window, as viewed

from the interior of a building, illustrating the horizontally pivoted ventilator sash in open position.

Figure 2 is an enlarged fragmentary face view of a portion of the window frame and ventilator frame in closed position, detailing the pivotal mounting structure which connects the sash frame to the window frame.

Figure 3 is an enlarged fragmentary rear view, as projected from Figure 2, partially broken away to further illustrate the pivotal mounting structure of the ventilator sash.

Figure 4 is a cross sectional view taken on line 4-4, Figure 2, detailing the structure of the sash frame and its relationship to the window frame in closed position, in a plane above the pivotal axis of the ventilator sash.

Figure 5 is a cross sectional view taken on line 5-5, Figure 6, detailing the pivotal mounting of the sash frame with respect to the window frame.

Figure 6 is a cross sectional view taken on line 6-6, Figure 2, illustrating the frame structure in a plane below the pivotal axis and showing the relationship of the sash frame to the window frame in closed position.

Figure 7 is a longitudinal sectional view, taken on line 7-7, Figure 2, further detailing the pivotal mounting structure with particular reference to the sealing sector at the pivotal axis of the ventilator frame.

Figure 8 is a sectional view similar to Figure 7 showing the ventilator frame in open position with respect to the window frame, corresponding to Figure 1, and further illustrating the operation of the sealing sector in conjunction with the pivot pin.

Figure 9 is an enlarged diagrammatic view taken from Figure 8, further illustrating the seal of Figure 8.

Described generally with reference to Figure 1, the window frame, which is indicated at 10, is fabricated from metal framing members, preferably steel, and follows a design conventionally employed in the construction of commercial buildings in which the window frame is set in masonry walls. The frame includes a marginal flange or masonry fin 11 which is embedded in the masonry wall opening and which provides a weatherproof joint with respect to the opening. In the present structure, which is intended to disclose a preferred embodiment of the invention, the window frame 10 includes a pair of fixed window panes 12-12 respectively at the top and bottom, and a ventilator sash indicated generally at 13, which is pivoted intermediate its length for movement about a horizontal axis with respect to the frame.

Both the window frame and ventilator frame proper are fabricated from steel framing members which are usually hot rolled to provide the necessary configuration in cross section as explained in detail later. The adjoining ends of the framing members are mitered and joined by welding or riveting in a conventional manner. It will also be understood that the external masonry fin 11 is conventional and is furnished in various forms. These fins or like members are interfitted in suitable slots formed in the masonry window opening and thus lock the window frame rigidly in position. In order to provide a weather seal, a grouting or caulking compound is packed into the slot and around the fin, depending upon the particular type of installation.

The sash mounting structure of the present invention is interrelated with the window frame, and as explained later in detail, the mounting structure is in the form of cooperating weathering strips pivoted together and attached respectively to the window frame and ventilator frame. As best shown in Figure 1, the window frame 10 includes an opening 14 in which the ventilator sash is pivoted, and which cooperates with the sash to provide a weather seal about the ventilator sash when it is closed.

Described in detail with reference to Figure 1, the window frame 10 includes the vertical jambs or side rails 15-15, and top and bottom horizontal rails 16-16, all consisting of steel angle irons as illustrated in Figure 4. One limb of the angle iron provides the masonry fin 11

and the second limb, which is indicated at 17, delineates the internal frame of the window, and includes an internal flange 18.

It will be noted at this point, that flange 18 forms a seat for the glass panels or panes 12 at the top and bottom of the window frame and that it also projects inwardly along the sides of opening 14, providing a stop engageable by the marginal edges of the ventilating sash 13. The opening 14 additionally includes a head rail 20 and a sill 21, which delineate the top and bottom of opening, and which are engageable by the upper and lower edges of the ventilator sash when in closed position.

It will be understood that the flange 18 is continuous of the full internal perimeter of frame 10 and that the glass panes 12 are seated against the flange and sealed in by putty or glazing compound in the usual manner. The vertical divider rails 22-22 of the window frame are generally T-shaped in cross section to provide a pair of flanges similar to flange 18, suitable to engage the marginal edges of adjacent panes 12-12.

The ventilator sash 13 includes an external frame formed of rails 23 having generally T-shaped heads 24 (Figure 4) similar to the dividers 22 above noted. In the present disclosure, the ventilating sash is provided with vertical and horizontal divider rails 25-25, which are also T-shaped in cross section, similar to rail 23, adapted to mount the four glass panes 26. The ventilator sash is mounted for pivotal motion about a horizontal axis by means of the pivot pins 27-27 as described in detail later. The ventilating sash, as best shown in Figure 1, is provided with a chain or a cord 28, attached to the upper edge of the sash and anchored at its free end upon a hook 30, or the like which is attached to the divider rail 22 of the window frame. A latch 31 which is mounted upon the lower cross rail of the tiltable ventilator sash, is adapted to engage the lower rail or sill 21 in closed position, to lock the ventilator sash in closed position. The latch is of conventional construction and for this reason is not disclosed in detail. If desired, a notched bar (not shown) may be pivotally connected to the lower edge of the ventilator sash in the conventional manner. In this case, the notches engage the sill 21 and lock the sash in its selected open or closed positions.

As best shown in Figure 4, the side rails or framing members 23 of the ventilator sash, extending from the pivot point upwardly, are provided with sheet metal weathering strips of U-shaped cross section, indicated generally at 32, and secured to the leg 33 of the framing member by spot welding as indicated at 34. It will be noted that each U-shaped weathering strip thus provides two outwardly projecting limbs 35 and 36, which are adapted to provide a line contact respectively with the flange 18 and the end of leg 17 of the window frame, thus forming a double weather seal.

The weathering strips, as shown in Figure 4, extend upwardly from the pivot pins 27 along opposite sides of the ventilator sash and across the upper edge of the sash. In other words, the constructions along the two sides and top are identical to that shown in Figure 4, such that the limbs 35 and 36 contact the inner surfaces of the main window frame, allowing the upper portion of the ventilator sash to swing inwardly and the lower portion outwardly, as shown in Figure 1.

From the foregoing it will be apparent that the internal flange 18 of the main window frame provides an external marginal abutment for the glass panes 12 in the upper section of the window frame as indicated by the broken lines in Figure 4, and that the same flange functions as a stop for the ventilating sash within opening 14, as indicated in Figure 4.

It will also be apparent that the T-shaped framing member 23 of the ventilating sash provides a similar marginal frame for the glass panes 26 on one side, as indicated in broken lines in Figure 4 and provides a support for the U-shaped weathering strip 32 on its opposite side. By

virtue of this construction the flange 18 and head 24 provide abutment surfaces which lie in the same plane when the ventilator sash is closed, thus bringing the fixed and movable panes in a common vertical plane as indicated by the broken lines.

A similar mounting and weather sealing strip is provided for that portion of the ventilating sash which extends downwardly below the horizontal axis of the ventilator sash (Figure 6). Since this portion of the sash swings outwardly with respect to the fixed window frame, a weathering strip indicated at 37, similar to that shown in Figure 4 is utilized. In this case it is secured by spot welding to the leg 17 of the main window frame such that the strips are stationary and the sash moves relative to them. It will be noted in this instance, that the position of the U-shaped weathering member 37 is reversed and that the limbs 35 and 36 project inwardly toward the movable sash. Thus the head 24 of the T-shaped sash framing member contacts the external surface of limb 35 and the inner end of leg 33 of the framing member contacts the external surface of 36. In this manner a double weather seal, similar but reversed from that disclosed in Figure 4, is provided for the lower portion of the ventilator sash. The structure shown in Figure 6 extends from the intermediate axis of the ventilator sash downwardly along opposite sides and across the lower cross rail as indicated in Figure 1.

It is to be observed that the abutment surfaces of flange 18 and head 24 lie in a common vertical plane when the ventilator sash is closed, as shown in Figure 6, so that the panes of the fixed frame and ventilator sash are flush with one another as explained above. It will be apparent, therefore, that when the ventilator sash is in closed position, an efficient weather seal is provided around the entire perimeter of the ventilator sash relative to the window frame. The double line seal provided by the spaced limbs 35 and 36 forms a dead air space which is effective to prevent leakage of air and prevent drafts due to wind pressure during stormy weather.

As explained earlier, the pivot pins 27, preferably are located upon an axis slightly above the center line of the sash in relation to its vertical extent, in order to overbalance the sash in closing direction. The pivot pins are thus disposed above the horizontal dividers 25, which are located at the center line, as shown in Figure 2.

The pivotal joint is one of the significant aspects of the invention and is incorporated in the weathering strips as an integral part of them by a simple severing and stamping operation. The weathering strips are fabricated from a relatively heavy gauge sheet metal and the joint, which is generally of double U-shaped configuration in cross section, provides several sheet metal sections spaced along the axis of the pivot pin. By virtue of the plural metal sections a large radial bearing area is provided which distributes the load, and in addition, the joint provides generous axial bearing surfaces which stabilize the sash transversely.

As best shown in Figure 2, the adjoining intermediate ends of the upper and lower weathering strips, 32 and 37, are provided with respective tenons or hinge sections 38, which interfit one another at the joint in side-by-side relationship. The U-shaped tenons, which are identical with one another, are formed by partially severing the limb 36 of each weathering strip transversely as indicated at 40-40 in Figure 2. Each partially severed sheet metal section is then bent inwardly toward the limb 35 to provide a U-shaped section, which is slightly less than half the width of limb 36, as shown in Figure 5. The severed metal sections, upon being bent to U-shape, provide the respective limbs 41-41, which reside in contact with one another, when the tenons are pivoted together. It will be noted that the two limbs thus provide an interface having a substantial area which forms a smooth acting, durable axial bearing.

Upon reference to Figure 5, it will be observed that

5 10 15 20 25 30 35 40 45 50 55 60 65 70 75

the pivot pin 27 projects through the legs 17 and 33 of the window and sash frame, through the webs of the respective weathering strips, and also through the intermediate limbs 41-41. This provides six metal bearing sections, which are effective to bear the load. The arrangement of the tenons, with respect to the window and sash frame, thus provides an exceptionally long stabilized bearing having a generous bearing load surface without the addition of metal.

As best shown in Figure 3, the contact sector 42 resides in a position underlying the external limb 35 of the upper weathering strip. The sector is developed upon a radius, the center of which is located below the axis of pivot pin 27, as is indicated diagrammatically in Figure 9. The geometric relationship is such that the lower end 43 of limb 35 establishes a wedging engagement with the surface of the sector, as indicated in broken lines in Figure 9, when the sash is closed. It will be observed that the edge 43 is located in a plane which extends through the axis of the pivot pin when the sash is closed, whereas the center of the sector lies below the axis of the pivot pin. Thus as the edge 43 swings in its arc from open to closed position, its curved path of motion converges toward the curved surface of the sector and wedges against it to provide a line seal when the sash is fully closed.

Upon reference to Figures 2 and 5, it will be noted that the contact sector 42 is formed as an integral part of the limb 35 and underlies the lower end of the corresponding limb of the upper weathering strip. It will also be seen that the line seal, which the contact segment forms, extends across and beneath the heads 18 and 24 of the framing members 15 and 23; therefore the heads overlie the major part of the joint when the sash is closed. The sector completes the perimeter seal formed by the weathering strips and is presented to the exterior of the window unit to prevent entry of water into the weathering strips and pivot pins from the exterior of the window unit when exposed to storms and driving rains. It will be understood that the clearances 44, which are provided at the ends of the tenons (Figure 2), are open to the interior of the building and require no weatherproofing.

During manufacture, the tenons and contact sectors are formed accurately, preferably by a punch and die operation, after which the holes are pre-punched in the tenons and in the framing members to receive the pivot pins. The upper and lower weathering strips are then located accurately relative to the window frame and sash by inserting a gage pin through the holes of the framing members and tenons and the strips are then spot welded to the framing members. The pivot pins are then inserted through the matching holes and peened over to form a permanent assembly with the sash properly located with respect to the frame. Reversible pivot pins 45, as indicated in broken lines in Figure 5, may also be provided for those conditions where it is desired to leave removable ventilators. In that case the pivot pins have a cotter pin 46 on one side and a head on the other. After assembly of the sash and frame, the glass panes are inserted and the glazing putty applied, as indicated in Figures 4 and 6.

Throughout the present disclosure, the ventilating sash is supported by the weathering strips which extend downwardly below the pivot pins, such that the upper portion of the sash swings inwardly and the lower portion outwardly. However, in the event that it is necessary to reverse the direction of swing, the position of the respective weathering strips may be reversed, such that the support strips are secured to the window frame above the pivot pins to permit the upper portion of the sash to swing outwardly and the lower portion inwardly. In this event, the second set of weathering strips, which is attached to the lower portion of the ventilator sash, will extend from the pivot pins downwardly.

From the foregoing description, it will be apparent that the pivot structure forms an integral part of the window

unit and requires no separate parts, with attendant welding of separate attaching means. The structure completely conceals and protects the pivot bearings and thus eliminates the possibility of damage during shipment or in use, since there are no protruding parts. The hinge further provides generous bearing surfaces, both radially and axially, to provide easy operation and long service without undue wear and with little or no service or maintenance.

Having described my invention I claim:

1. A pivotal mounting structure for a window unit having a stationary window frame and a sash frame mounted therein for tilting motion along a horizontal axis to an open or closed position, said mounting structure comprising, a pair of stationary mounting strips and a pair of pivotal mounting strips, said stationary and pivotal mounting strips being U-shaped in cross section having a web and an inner and outer limb, a hinge tenon on the end portion of each strip, each tenon being substantially half the width of said outer limb and being offset laterally to the web of the mounting strip, each tenon having a length substantially equal to the width of said outer limb, each tenon formed by severing said outer limb along a line extending transversely from the free edge thereof toward said web, said severed portion bent inwardly at right angles to the plane of the outer limb and providing an inturned limb spaced outwardly from the web, the webs of the stationary mounting strips being facially secured to a respective opposite side of the stationary frame with said limbs projecting inwardly toward one another and the offset hinge tenons thereof projecting across the said horizontal axis, the webs of the pivotal strips being facially secured to the sash frame with the limbs projecting outwardly from opposite sides of the sash frame and the offset hinge tenon thereof projecting across said horizontal axis from a direction opposite to the tenons of stationary strips, the offset hinge tenons of said stationary and pivotal mounting strips being nested lengthwise with the respective inturned limbs thereof residing in facial bearing engagement with one another, and a respective pivot pin projecting through the nested hinge tenons on opposite sides of the window unit, said pivot pins disposed along said horizontal axis, the weight load of the sash frame being carried by said nested hinge tenons and pivot pins.

2. A pivotal mounting structure for a window unit having a stationary window frame and a sash frame mounted therein for tilting motion along a horizontal axis to an open or closed position, said mounting structure comprising, a pair of stationary mounting strips and a pair of pivotal mounting strips, said stationary and pivotal mounting strips being U-shaped in cross section having a web and an inner and outer limb, a hinge tenon on the end portion of each strip, each tenon being substantially half the width of said outer limb and being offset laterally to the web of the mounting strip, each tenon formed by severing said outer limb along a line extending transversely from the free edge thereof toward said web, said severed portion bent inwardly at right angles to the plane of the outer limb and providing an inturned limb spaced outwardly from the web, the web of each stationary mounting strip being facially welded to a respective opposite side of the stationary frame with the offset hinge tenons thereof projecting upwardly across the said horizontal axis, the web of each pivotal mounting strip being

ing facially welded to the sash frame with the offset hinge tenons thereof projecting downwardly across said horizontal axis, the offset tenons of the stationary and pivotal mounting strips being nested lengthwise with the respective inturned limbs thereof residing in facial bearing engagement with one another, and a respective pivot pin projecting through the sash frame and stationary frame and through the said nested tenons, said pivot pins residing along said horizontal axis, the weight load of the sash frame being carried by said hinge tenons and pivot pins, said hinge tenons and frames providing multiple load bearing sections spaced along the axis of each pivot pin, the weight load of the sash frame being carried by the said multiple load bearing sections and pivot pins.

3. A pivotal mounting structure for a window unit having a stationary window frame and a sash frame mounted therein for tilting motion along a horizontal axis to an open or closed position, said mounting structure comprising, a pair of stationary mounting strips and a pair of pivotal mounting strips, said stationary and pivotal mounting strips being U-shaped in cross section having a web and an inner and outer limb, a hinge tenon on the end portion of each strip, each tenon being substantially half the width of said outer limb and being offset laterally to the web of the U-shaped strip, each tenon formed by severing said outer limb along a line extending transversely from the free edge thereof toward said web, said severed limb portion bent inwardly at right angles to the plane of the outer limb and providing an inturned limb spaced outwardly from the web, the web of each stationary mounting strip being facially welded to a respective opposite side of the stationary frame with the offset hinge tenons thereof projecting upwardly across the said horizontal axis, the web of each pivotal strip being facially welded to the sash frame with the offset hinge tenons thereof projecting downwardly across said horizontal axis, the offset tenons of the stationary and pivotal mounting strips being nested lengthwise with the respective inturned limbs thereof in facial bearing engagement with one another, a respective pivot pin projecting through the nested hinge tenons, said pivot pins disposed along said horizontal axis, the weight load of the sash frame being carried by said hinge tenons and pivot pins, a contact sector formed on the upper end of the outer web of each stationary mounting strip, said sector being curved in an arc extending upwardly from the outer web inwardly toward the pivot pin and passing beyond the axis thereof, the outer web of each pivotal mounting strip having a free lower end adjacent said contact sector, said free edge swinging in an arc which converges downwardly toward the curved sector as the sash frame tilts toward the closed position, said free edge providing a wedging engagement with said sector when the sash frame is in closed position.
